UNITED STATES PATENT OFFICE.

THOMAS L. McKEEN, OF EASTON, PENNSYLVANIA.

CAR-COUPING.

SPECIFICATION forming part of Letters Patent No. 325,848, dated September 8, 1885.

Application filed May 23, 1885. (No model.)

To all whom it may concern:

Be it known that I, THOMAS L. McKEEN, of Easton, in the county of Northampton and State of Pennsylvania, have invented certain new and useful Improvements in Car-Couplers, of which the following is a full, clear, and exact description.

This invention more particularly relates to automatic railway - car couplers in which a sliding block, arranged within the draw-head and forced outward by a spring, and serving both as an elastic stop to the link when coupling, and as a support for the coupling-pin when raised, is used; and it consists in a certain attachment to said block for relieving the coupling-pin of friction when lifting it to uncouple, and in certain combinations or arrangements of parts of the coupler, including a stop connected with the lifting devices of the coupling-pin, not merely to prevent said pin from being wholly withdrawn from the draw-head, which has before been done in various ways, but to limit the lift of the pin for a proper operation of the attachment to the sliding block, which relieves the coupling-pin of friction when being lifted, and which supports it when raised, substantially as herein described.

Reference is to be had to the accompanying drawings, forming part of this specification, in which similar letters of reference indicate corresponding parts in all the figures.

Figure 1 represents an end view of a railway-car body in part, with my improved coupler applied; Figs. 2 and 3, vertical sections on the line xx in Fig. 1, showing, respectively, the coupling-pin as engaged and disengaged; Fig. 4, a view in perspective of the sliding block used in the coupler, and Fig. 5 a perspective view of the attachment to said block for supporting the coupling-pin when raised, and for relieving the pin of friction when uncoupling.

A indicates the one end of a car-body, and B its draw-head. C is the coupling-pin, and D the coupling-link. E is the cranked rocker in the draw-head, having an attached rocking fulcrum-pin, b , crossing the draw-head, and operated from the exterior, as by a lever, c , the whole serving to raise or lower and direct the link when coupling the cars.

G is the sliding block in the draw-head, directed in its movement by upper and lower guides, $d e$, and forced outward by a spring, f , till arrested by the rocking fulcrum-pin b of the link-rocking guide E, which thus serves to act as a stop to said yielding-block G when it reaches a proper position to receive the link shown in Fig. 2, and to support the coupling-pin D when raised to uncouple, as shown in Fig. 3. Said block, however, is not made to support the pin C when raised, directly, but through the intervention of an upper flap, H, pivoted to the block, or resting by trunnions g within grooved ways h therein, and so that when said flap is down or in a horizontal position, and the sliding block G is forced by its spring against the fulcrum-pin b of the link-guide E, as shown in Fig. 3, said coupling-pin-supporting flap projects beneath the coupling-pin to hold it raised. On running the cars together, however, to couple, the coupling-link, striking the block G, forces it and its attacher-flap H back, allowing the pin C to drop to couple, and afterward, on the recoil of the spring f , which brings the block G again up against the fulcrum-pin b of the link-guide, the coupling-pin-supporting flap H, which is of curved construction on the underside of its front for the purpose, is, by its striking the coupling-pin, turned up and restrained from being forcibly pressed by the spring f against the coupling-pin, as shown in Fig. 2, so that it will be free from that restrictive action and friction on the coupling-pin that the block G would have were it to be used as the direct support for the coupling-pin. Such yielding coupling-pin support H accordingly allows of a much freer and easier withdrawal of the coupling-pin and reduces wear, thus adding to the durability of the coupler.

The coupling-pin C may be raised to uncouple by means of a shaft, I, arranged across the end, or it might be top of the car, as in other car coupling and uncoupling mechanisms; but as it is not necessary or desirable to raise the coupling-pin wholly out of the draw-head, or to lift it higher than will allow the flap H to fall and adjust itself into a supporting position for said pin, I use a bell-cranked lever, J, on the shaft I, the one arm, K, of which

is connected by chain with the coupling-pin, and the other arm, *l*, of which acts as a stop against the car to prevent the undue or excessive lift of the coupling-pin, as shown in Fig. 3.

Instead of a bell-crank, two independent arms on the shaft, corresponding to the arms *K* and *l*, but in different planes, may be used.

It will be noticed that the stop-arm, applied to the shaft *I*, and arranged to restrict the upward movement of the coupling-pin to retain it, when raised, in the draw-head, acts conjointly with the pivoted flap *H* of the sliding block *G*—that is to say, said stop-arm determines the height to which the coupling-pin should be raised to admit of the pivoted flap *H* falling into position beneath the coupling-pin when raised, in order that it (the flap) may support said pin.

Having thus described my invention, what I claim as new, and desire to secure by Letters Patent, is—

1. In a car-coupler, the combination, with the draw-head *B*, its sliding block, *G*, and spring 25 for forcing out said block, of the coupling-pin-

supporting flap *H*, pivoted to said block, for operation in relation with the coupling-pin, substantially as specified.

2. The combination of the draw-head *B*, the sliding block *G*, and its spring *f*, the pivoted coupling-pin-supporting flap *H*, the coupling-pin *C*, and the rocking-link guide *E*, constructed and arranged to act as a stop to arrest the sliding block at the limit of its forward movement, essentially as described.

3. The combination, with the draw-head, coupling-pin of the coupler, and the sliding-block *G*, with its pivoted flap *H*, which supports the coupling-pin, when raised, of the shaft *I*, by which said pin is lifted when required to uncouple, and a stop-arm applied to said shaft, arranged to limit the height to which the coupling-pin should be raised to admit of the pivoted flap falling into position beneath said pin when raised, substantially as specified.

THOMAS L. McKEEN.
